UNITED STATES PATENT OFFICE.

WINFRED H. JUERGENS, OF CLEVELAND, OHIO.

PIPE-THREADING DIE-STOCK.

1,125,112.

Specification of Letters Patent. Patented Jan. 19, 1915.

Application filed March 10, 1914. Serial No. 823,654.

To all whom it may concern:

Be it known that I, WINFRED H. JUERGENS, a citizen of the United States, and resident of Cleveland, in the county of 5 Cuyahoga and State of Ohio, have invented certain new and useful Improvements in Pipe-THREADING Die-Stocks, of which I hereby declare the following to be a full, 10 clear, and exact description, such as will enable others skilled in the art to which it 15 appertains to make and use the same.

The object of the invention is to provide a die stock for cutting a taper screw thread upon pipes or other cylindrical products, 15 and the invention comprises a body portion and a movable member therein, in which screw cutting dies are slidably mounted and includes automatically acting means permitting progressively and continuously 20 moving the dies to lessen the depth of the cut and to produce taper threads as the threads are cut farther into the periphery of the work.

The invention further includes the combination and arrangement of parts and construction of the various details hereinafter described, shown in the accompanying drawings and specifically pointed out in the claims.

30 In the accompanying drawings Figure 1 is a central longitudinal section of the device; Fig. 2 is a plan view with the die covers removed; Fig. 3 is a plan view of a portion of the cam stud ring; Fig. 4 is a detail view of one of the operating cams; Fig. 5 is a perspective view of one of the dies; Fig. 5^a is a view of a cylindrical member used in place of one of the cams when a straight screw thread is to be cut; Fig. 6 40 is a plan view of a die stock showing stepping-blocks intermediate of the dies and cams, by means of which the dies can be adjusted to cut taper threads upon pipes of different diameters; Fig. 7 is a perspective 45 view of one of the stepping blocks; Fig. 8 is a perspective view of one of the dies adapted for use therewith; Fig. 9 is a plan view of one of the die covers; Fig. 10 is a transverse section of die and cover on line 50 x—x Fig. 9 showing the operating pin for one of the stepping blocks.

In these views A is an annular member which is passed over the end of the pipe upon which the screw threads are to be cut. 55 Within this member is secured a sleeve A' through which the pipe passes and to which it is secured by one or more set screws A².

A third member A³ provided with a lead screw a of the same pitch as the pitch of the threads to be cut on the pipe is attached to 60 the member A and is provided with a shoulder a' spaced from the end of the member A to form a bearing for the disk D hereinafter described. The members A, A' and A³ are stationary.

65 B is a rotatable disk or body which carries radially movable dies C, C, which move, in guide grooves B', B' and are regularly spaced in the disk B. These dies are provided with screw threads C, C, having cutting edges c², c², at the inner ends. The disk is provided with an integral tubular and central extension B² through which the pipe passes and which is externally screw threaded at b to correspond with the internal screw thread a upon the stationary member A³. Handles E, E, are attached to the disk B at F, F, by means of which the disk is rotated.

70 As shown in Figs. 1 and 2 in the disk B at the rear of the dies are rotatably secured the cams G, G which make contact with the ends of the dies and they are partially rotated with each movement of the disk to permit a progressive rearward movement 75 to the dies as the lead screws carry them farther up the end of the pipe.

75 The means for rotating the cams consists in the vertical studs H, H, which are mounted in the disk D which supports them and 80 rotates with the disk B. They are detachably secured to the disk D by means of screw threaded extremities d, d, and nuts d', d'. The studs H pass through openings g, g, in the cams, and are provided with spiral 85 grooves h', h' which are engaged by pins g', g' in the openings in the cams.

In operation, as the disk B revolves and is fed longitudinally of the stationary members A³ by means of the lead screws the 100 studs H, H, will pass through the cams and rotate the cams so as to permit the dies to move continually backward and the cutting edges of the dies will gradually be removed from the pipe, thus cutting a screw thread 105 of gradually decreasing depth in the end of the pipe. Over the dies and cam are placed the retaining caps or cover I, I, which are provided with inclosed openings I' I' to receive the ends of the studs as they are forced through the cams. The dies are prevented from falling out by means of spring pressed balls Q, Q, which lie in grooves Q', Q' in the dies, and permit a certain amount of 110

movement in the dies, while limiting its extent. Adjusting screws Q^2 , Q^2 pressing upon the springs Q^3 , Q^3 , permit of the control of the amount of pressure exerted thereby.

When fine adjustment of the dies is required to produce threads a trifle oversize or undersize, or of standard size, the bases W upon which the operating studs for the cams are set are provided with a series of spaced openings circularly arranged therein, and each stud is provided with a parallel pin X adapted for selective insertion in said holes, thus varying the angle of advance or retard of the studs and having a similar effect upon the cams. The central opening w of each series of openings will control the standard size, the holes at the left the undersize and the holes at the right the oversize.

In Figs. 6, 7, 8, 9, and 10 an additional feature is introduced showing a stepping block V introduced between each die block and cam, permitting the die to be advanced to cut threads upon several sizes of pipe, and provided with several surface levels, v , v' , v^2 , v^3 , against which the die block will rest when cutting pipes of two inch, $1\frac{1}{2}$ inch, $1\frac{1}{4}$ inch and 1 inch diameter respectively, or of any other required dimension.

The die block is cut away at v^4 , to provide clearance as the extremity of the die block engages the several steps upon the stepping block. In the cover for the dies and stepping block a slot S is formed and in this slot and into an opening S' in the stepping block a pin S^2 is inserted by means of which the stepping block is moved from one position to the other. An index upon the cover at one side of the slot permits the necessary adjustment to be made.

Having described the invention what I claim as new and desire to secure by Letters Patent is:

1. In a die stock for cutting a tapering screw thread, in combination, a tubular stationary portion provided with a lead screw, a revolute body portion provided with a corresponding lead screw and having a central opening, and radial guides therein, dies movable in said guides, a cam for operating each die and having a central opening, a revolute disk upon said stationary member, studs projecting from said revolute disk through said opening in said cams, said studs provided with spiral engaging means, and corresponding engaging means upon said cams in said central openings therein.

2. In a die stock, in combination, a tubular stationary member provided with a lead screw, a tubular body rotatable thereon, and provided with a corresponding lead screw, dies radially movable in said tubular body, cams rotatably mounted in said tubular

body, each cam operating one of said dies and having an opening, a spirally grooved stud passing through the opening in each cam, each cam provided with engaging means for the grooves in said studs, and a support rotatable with said tubular body for said studs.

3. In a die stock, in combination, a tubular stationary member provided with a lead screw, a rotatable tubular body provided with a corresponding lead screw and mounted thereon, dies radially movable in said tubular body, a rotatable cam for operating each die and having a central opening, a spirally grooved stud passing through each cam opening, engaging means on each cam for said grooves in said studs, a member revolute with said tubular body to which all said studs are rotatably secured, and means for adjusting the angular position of each stud upon said support to control the amount of advance and retard of said cams.

4. In a die stock, in combination, a stationary tubular member provided with a lead screw, a tubular body member rotatable thereon and provided with a corresponding lead screw, dies radially movable in said tubular body, cams for operating said dies, spirally grooved studs passing through and engaging said cams a common support for said studs, said support rotatable with said tubular body, and covers for said dies, cams and studs, said covers permitting the free operation thereof, and means for limiting the movement of said dies.

5. In a die stock, in combination, a stationary tubular member provided with a lead screw, a tubular body rotatable thereon and provided with a corresponding lead screw, dies radially movable in said body, stepped blocks engaging said dies and adjustable in said body, cams rotatable in said body and engaging said stepped blocks, and means for automatically rotating said cams to progressively advance said stepped blocks and dies as said body is advanced by said lead screw.

6. The combination in a die stock, of a tubular rotatable member having a lead screw, and a tubular stationary member having a corresponding lead screw, dies radially movable in said body, adjustable stepped blocks engaging said dies, cams engaging said stepped blocks and means for adjusting said stepped blocks and for rotating said cams to control the advance of said stepped blocks and said dies.

In testimony whereof, I hereunto set my hand this 14th day of February 1914.

WINFRED H. JUERGENS.

In presence of—

W.M. J. KLOTZBACH,
W.M. M. MONROE.
